BRICK VENEER CONSTRUCTION MATERIAL
Robert K. Stout, Rte. 1, Norwalk, Iowa
Filed Oct. 31, 1958, Ser. No. 770,935
5 Claims. (Cl. 59—341)

My invention relates to structural clay products and more particularly to a veneer material for creating a brick-like finish on a wall surface or the like.

The building of a brick or masonry wall is one of the more expensive aspects in construction costs. This is true because of the relative slowness in constructing such a wall from small brick elements, the high degree of skill required by the craftsman who builds the wall, and the difficulty in handling and moving the brick and mortar on a construction job.

Therefore, the principal object of my invention is to provide brick veneer construction material which can be rapidly installed.

A further object of my invention is to provide brick veneer construction material that is light in weight and which can be easily transported.

A still further object of my invention is to provide a brick veneer construction material which will create a realistic appearance of a brick or masonry wall.

A still further object of my invention is to provide a brick veneer construction material whose mortar joints can be created in one continuous operation rather than a plurality of successive operations.

A still further object of my invention is to provide a brick veneer construction material that will be protected from smearing by the mortar during the installation operation.

A still further object of my invention is to provide a brick veneer construction material that is economical of manufacture, durable in use and refined in appearance.

These and other objects will be apparent to those skilled in the art.

My invention consists in the construction, arrangement, and combination, of the various parts of the device, whereby the objects contemplated are attained as herein-after more fully set forth, specifically pointed out in my claims, and illustrated in the accompanying drawings, in which:

FIG. 1 is a perspective view of one specie of my device with portions of the brick slabs cut away to more fully show its construction;

FIG. 2 is an end elevational view of another specie of my device which has been rolled up for carrying or transportation purposes;

FIG. 3 is an elevational view of my device as it is being installed;

FIG. 4 is a sectional view of my device taken on line 4—4 of FIG. 3;

FIG. 5 is a perspective view of a particular specie of my device; and

FIG. 6 is an enlarged, fragmentary perspective view of my device wherein continuous wires are used.

The numeral 10 designates a sheet of flexible corrugated cardboard which has its conventional webbing 12 preferably disposed in a horizontal position. Sheet 10 should be impervious to moisture and this can be accomplished in any of the conventional coating or impregnating methods to which cardboard is usually subjected for such purposes. Sheet 10 in FIG. 1 is rigid.

Wire mesh 14 is secured to one side of sheet 10 by a suitable adhesive 16. This same adhesive 16 can be used to secure a plurality of spaced apart brick slabs 18 to the mesh 14 and the sheet 10. As shown in FIGS. 1, 2 and 3, the elongated, thinly constructed slabs 18 are preferably disposed in a horizontal fashion with a uniform opening or void 20 surrounding each parallel slab. Thus,

2

a stack bond can be created by the slabs 18 as shown in FIG. 3. Each slab 18 has a plurality of vertical cores 19 through which wires 21 can extend to interlace the slabs to mesh 14. A protective sheet 22 of paper or the like is secured to the outer face of slabs 18 by a suitable adhesive (not shown) which has no specific requirements other than the ability to permit the sheets 22 to be selectively removed from the slabs.

Referring particularly to FIG. 6, portions of adjacent slabs 18 are shown in combination with the sheet 10 of cardboard to which the wire mesh 14 has been affixed by the adhesive 16 (FIG. 4). The slabs 18 are so arranged horizontally that the openings or voids 20 therebetween are uniform as described hereinbefore. Each slab 18 has a plurality of two or more of the horizontally spaced, vertically disposed cores 19, and the extensions through each core 19 and its vertically adjacent core 19 of the continuous wire 21 is clearly depicted. In between each vertically spaced pair of slabs 18, each wire 21 as it passes through the void 20 is threaded underneath a portion or strand of the wire mesh 14 so as to connect the slabs to the wire mesh 14 at location above and below slabs 18. Thus a plurality of continuous wires 21 are passed through a plurality of parallel cores 19 in one slab 18, and with each wire 21 passed through vertically adjacent and aligned cores 19 in slabs 18 above and below the one slab 18, with each wire 21 interlaced with the wire mesh 14 in between each vertically adjacent slabs 18.

30 The numerals 24, 26 and 28 designate 2" x 4" wood studdings which are customarily used in wall construction. FIG. 4 shows nails 30 penetrating the cardboard sheet 10 and wire mesh 14 at points in between brick slabs 18 to hold my device to the studding members. The numeral 32 designates grout which has been used to fill voids 20.

35 FIG. 5 shows a particular specie of my device which also utilizes the cardboard sheet 10 and wire mesh 14. But instead of adhering a plurality of individual brick slabs to the wire mesh and cardboard sheet, a larger tile 34 is used. Tile 34 has the same substantial thickness as slabs 18. The outer face of tile 34 is scored to create a plurality of parallel voids 36. The areas between voids 36 are comparable to the shape and area of slabs 18. Thus, the tile 34 presents an outer surface very similar to that created by brick slabs 18. As shown in FIG. 5, the individual tiles 34 are spaced apart a distance equal to the breadth of voids 36. Reinforcing webs 38 and 40 can extend outwardly along the inner face of tile 34 for strengthening purposes. Web 38 extends in a vertical direction and webs 40 extend in a horizontal direction. 45 Because of the great strength these webs give my unit, I prefer that one or both of them be utilized. The tiles 34 are secured to wire mesh 14 and cardboard sheet 10 by the adhesive 16. The portion of tile 34 between voids 36 is 50 also covered by sheets 22.

55 I prefer that my device be fabricated in 4'0" x 8'0" sheets which would permit three 15½" brick slabs to extend across sheet 10 in each course of brick. My device is satisfactory for use on both internal and external walls.

60 My device is usually transported in rolls as shown in FIG. 2, and all elements of the product are intact except for the grout material 32. The rolls can easily be formed because of the flexible nature of cardboard 10 and wire mesh 14.

65 After studding members 24, 26 and 28 have been erected in conventional manner, my device is unrolled to form a substantial flexible sheet. Its weight is greatly reduced because the brick slabs 18 (or tile 34) are relatively light in weight. The spaces between the studding members are substantially equal to the horizontal lengths of either the slabs 18 or tile 34. Nails 30 are used to se-

cure the cardboard sheet 10 and wire 14 to the studding in the manner described above.

After my device has been nailed to the studding members, grout 32 can be inserted into the voids 20 between slabs 18 or into the voids 36 of tile 34. If the tiles are being used, the voids between the spaced tiles are similarly filled. The insertion of the grout 32 into the various voids creates the necessary mortar joints and conceals the heads of nails 30. After the grout 32 has been placed in the voids and has dried, the protective sheets 22 are manually pulled from the outer surfaces of slabs 18 or tile 34, thus leaving the outer surfaces thereof completely free from grout. Ordinarily, acid and heavy scrubbing are required to clean a brick wall after it has been constructed by conventional methods.

I have found that my invention works very well even when used in combination with the rigid board 10' shown in FIG. 1. It should be noted that a random bond could be used in the mounting of brick slabs 18 instead of the stack bond shown in the drawings.

Thus, from the foregoing, it is seen that my invention will accomplish at least all of its stated objectives.

Some changes may be made in the construction and arrangement of my brick veneer construction material without departing from the real spirit and purpose of my invention, and it is my intention to cover by my claims, any modified forms of structure or use of mechanical equivalents which may be reasonably included within their scope.

I claim:

1. In a veneer construction material, a sheet member, a wire mesh material secured to said sheet member, a plurality of brick slabs secured to said wire mesh and said sheet member, said brick slabs being disposed on said wire mesh and said sheet member in parallel courses, said slab members having parallel core openings extending therethrough in one direction, a first continuous wire extending through the core opening in one of said brick slabs, and thence extending through a single core opening in a brick slab in each of said courses, a plurality of continuous wires extending through other core openings in other brick slabs in the same manner as said first continuous wire; each of said continuous wires being interlaced with said wire mesh material at points intermediate said brick slabs.

2. In a veneer construction material, a flexible sheet member having oppositely disposed outer surface areas, a flexible wire mesh material secured to one outer surface area of said sheet member and engaging only said one outer surface of said sheet member, said wire mesh being secured to said sheet member by an adhesive substance, a plurality of brick slabs secured to said wire mesh and said sheet member, said brick slabs being disposed on said wire mesh and said sheet member in parallel courses, said slab members having parallel core openings extending therethrough in one direction, a first continuous flexible metal wire threadably loosely extending through the core opening in one of said brick slabs, and thence similarly extending through a single core opening in a brick slab in each of said courses, a plurality of continuous wires extending through other core openings in other brick slabs in the same manner as said first continuous wire; each of said continuous wires being interlaced with said wire mesh material at points intermediate said brick slabs.

3. In a veneer construction material, a flexible sheet member having oppositely disposed outer surface areas, a flexible wire mesh material secured to one outer surface area of said sheet member and engaging only said one outer surface of said sheet member, said wire mesh being secured to said sheet member by an adhesive substance, a plurality of brick slabs secured to said wire mesh and said sheet member, said brick slabs being dis-

posed on said wire mesh and said sheet member in parallel courses, said slab members having parallel core openings extending therethrough in one direction, a first continuous flexible metal wire threadably loosely extending through the core opening in one of said brick slabs, and thence similarly extending through a single core opening in a brick slab in each of said courses, a plurality of continuous wires extending through other core openings in other brick slabs in the same manner as said first continuous wire; each of said continuous wires being interlaced with said wire mesh material at points intermediate said brick slabs; said slab members having voids therebetween capable of receiving a grout material.

4. In a veneer construction material, a flexible sheet member having oppositely disposed outer surface areas, a flexible wire mesh material secured to one outer surface area of said sheet member and engaging only said one outer surface of said sheet member, said wire mesh being secured to said sheet member by an adhesive substance, a plurality of brick slabs secured to said wire mesh and said sheet member said brick slabs being disposed on said wire mesh and said sheet member in parallel courses, said slab members having parallel core openings extending therethrough in one direction, a first continuous flexible metal wire threadably loosely extending through the core opening in one of said brick slabs, and thence similarly extending through a single core opening in a brick slab in each of said courses, a plurality of continuous wires extending through other core openings in other brick slabs in the same manner as said first continuous wire; each of said continuous wires being interlaced with said wire mesh material at points intermediate said brick slabs; and protecting sheet members detachably secured to the outer face of said slab members.

5. In a veneer construction material, a sheet member having oppositely disposed outer surface areas, a wire mesh material secured to one outer surface area of said sheet member and engaging only said one outer surface area of said sheet member, said wire mesh being secured to said sheet member by an adhesive substance, a plurality of brick slabs secured to said wire mesh and said sheet member, said brick slabs being disposed on said wire mesh and sheet member in parallel courses, said slab members having parallel core openings extending therethrough in one direction, a first continuous flexible metal wire threadably loosely extending through the core opening in one of said brick slabs, and thence similarly extending through a single core opening in a brick slab in each of said courses, a plurality of continuous wires extending through other core openings in other brick slabs in the same manner as said first continuous wire; each of said continuous wires being interlaced with said wire mesh material at points intermediate said brick slabs.
